UNITED STATES PATENT OFFICE.

FRANK H. BALL, OF DETROIT, MICHIGAN, ASSIGNOR, BY DIRECT AND MESNE ASSIGNMENTS, TO BALL & BALL CARBURETER COMPANY, OF DETROIT, MICHIGAN, A CORPORATION OF MICHIGAN.

CARBURETER.

1,292,563.

Specification of Letters Patent. Patented Jan. 28, 1919.

Application filed April 20, 1916. Serial No. 92,539.

To all whom it may concern:

Be it known that I, FRANK H. BALL, a citizen of the United States, residing at Detroit, in the county of Wayne and State of Michigan, have invented new and useful Improvements in Carbureters, of which the following is a specification.

This invention relates to carbureters and consists in certain improvements in the construction thereof as will be hereinafter fully described and pointed out in the claims.

The invention is illustrated in the accompanying drawings as follows:—

Figure 1 shows a section through the carbureter on the line 1—1 in Fig. 2.

Fig. 2 a section on the lines 2—2 in Figs. 1 and 3.

Fig. 3 a side elevation of the carbureter.

The carbureter is formed of two main parts, 1 the body having the controlling devices including the mixing chamber and the float chamber 2 with its parts. The part 1 has the mixing chamber 3 at its upper end in which there is arranged a throttle 4. The throttle 4 is in the form of a butterfly valve mounted on the stem 4^a and extending to without the body. The controlling lever 5 is fixed on the stem 4^a and any convenient means (not shown) for controlling the throttle extends from the lever 5.

The fuel is supplied to the mixing chamber through the nozzle 6. The nozzle is arranged in a nozzle fitting 7 in the form of a screw having the passage 9. The fitting 7 is screwed into the nozzle passage 8, this passage having a stepped opening, the opening of smaller diameter receiving the fitting 7 and that part of larger diameter being of sufficient size to receive the head of the screw.

40 A plug 10 is screwed into the larger diameter of the nozzle passage. It has a central opening 11 extending downwardly from its top and this is connected by a restricted radial opening 12 with an annular passage 13 formed by reducing the size of the plug 10. A horizontal passage 14 formed in the body 1 leads to the annular passage 13. The horizontal passage 14 communicating with the lower end of a tubular chamber 15. The 45 lower end of the tubular chamber 15 is closed by a plug 16 which has a reduced portion forming an annular passage 17. The plug 16 is screwed into the tubular chamber 15,

the screw threaded portion being above the horizontal passage 14 so that the annular passage 17 forms a means of communication but the upper part of the chamber 15 is separated from the main body of this passage. The float chamber 2 has a projection 18 with an opening through it of the same size and registering with the bottom of the tubular chamber 15 and the screw plug 16 extends through this opening thus clamping the projection to the bottom of the body 1 thus forming a means of connection between the two main parts of the carbureter. The passage 19 extends from the bottom of the float chamber to the opening in the projection 18 and forms a means of communication between the float chamber 20 and the annular passage 17. It will be readily seen, therefore, that the float chamber is in direct connection with the nozzle and that the level of fuel at the nozzle will be that maintained by the float in the float chamber.

The flow of fuel to the float chamber is controlled by the needle valve 20 acting on the valve seat 21. The valve seat is arranged in a screw plug 22 having the axial passage 23. The screw plug extends into a screw 24 threaded projection on the bottom of the float chamber. The valve stem 31 extends through a guide 25 at the top of the screw plug and the axial passage in the screw plug is connected with the float chamber by the 26 radial passages 26. The float 27 is slidably mounted on the stem 31 and operates against the weighted levers 28. These levers are pivoted between the ears 29 and engage a spool 30 fixed on the stem 31. The ears 29 extend downwardly from a removable cover 32 and the stem extends upwardly through the cover and into a removable cap 33.

Fuel is delivered to the inlet passage 34 from any convenient source of supply. The 95 inlet passage is in a projection extending from the sleeve 35. The sleeve 35 is clamped on the bottom of the float chamber by means of the internally screw threaded plug 37 which is screwed onto the projection 24. 100 The screw 37 has an axial opening 38 communicating with the passage leading to the float chamber and radial openings 39. It has an annular groove 40 extending around it and the sleeve 35 has an annular groove 105 36 around it, these grooves forming a cham-

ber. A strainer 41 is arranged over the screw 37 taking an intermediate position in the chamber formed by the grooves 40 and 36. It will be readily seen that the gasoline is strained by this strainer and that by its annular shape sufficient capacity is given to the strainer.

An air passage 47 is arranged around the nozzle and forms an initial air passage leading to the mixing chamber. The passage is so arranged that the air passing through it takes up the fuel from the nozzle 6. The air led through the passage 47 is taken from the passage 48 and the secondary air passage 49 extends from the passage 48 to the mixing chamber 3. The passage 49 has an extension 50 of larger diameter than the passage proper and the passage 50 is surrounded by a seat 51 on which the air valve 52 rests. The air valve is slidingly mounted on the pin 53 carried by the adjustable nut 54. A spring 55 extends between the nut 54 and the valve 52 and resists the opening of the valve 52. The spring may be adjusted by screwing the nut 54 in and out as desired. A pin 56 is arranged in the end of the pin 53 and prevents the escape of the valve 52 from the pin 53 when the nut 54 is entirely removed from the body of the carbureter. The large valve 52 with the extension 50 on the passage 49 limits the influence of the valve on the flow of air to a very short period during the initial opening of this valve. In the later stages of the operation of this carbureter the flow of air for all practical purposes is controlled by the size of the opening 49 so that in these later stages the carbureter operates largely as one having fixed orifices or passages for the air and fuel. The extent of the control of the air by the valve may be varied by the nut 54.

Air is delivered to the passage 57 through an opening 48. This opening is cylindrically shaped and a choke valve 58 is arranged in this opening. The valve 58 is of the butterfly type and is mounted on a stem 59 which extends through the walls of the opening 48. An arm 60 is arranged on the stem 59 by means of which the choke valve 58 may be adjusted. In this carbureter the variation in quality is accomplished by the adjustment of this choke valve. This varies the resistance to the flow of air and consequently the quantity of fuel which is delivered with a given reduction of pressure in the mixing chamber. For this reason the usual needle valve for adjusting the fuel flow is not necessary. Such an adjustment so varies the capacity of the carbureter that where the single apparatus is used such as is thus far described it is not usually desirable but where the carbureter is supplemented as with this carbureter with a secondary carbureter taking care of the ultimate capacity this adjustment is of importance because while

it makes the adjustment of the primary carbureter possible without the additional adjustment of the fuel passage it does not have sufficient influence on the ultimate capacity to interfere with the general operation of the carbureter. While choke valves have been used to momentarily vary the quality of mixture as at starting it has not been practical to utilize this for the normal adjustment because of its effect on the ultimate capacity of the carbureter.

The secondary carbureter is as follows: Extending at a downward slant from the mixing chamber is an opening 61. This is initially closed by a butterfly valve 62. The butterfly valve 62 is carried by a stem 63, this stem extending through the walls of the carbureter. An arm 64 is fixed on the stem 63 (see Fig. 3). A pin 65 extends from the outer end of this arm and the spring 66 is secured to the pin 65 and to a pin 67 arranged on the outer wall of the carbureter. This spring tends to hold the valve 62 in its closed position as clearly shown in Fig. 1. A roller 68 is arranged in the end of the arm 64 and this is in the path of an arm 69 extending from the throttle lever 5. The length of the arm 64 with relation to the arm 65 is very short so that a comparatively slight movement of the arm 69 will move the arm 64 sufficiently to move the valve 62 from closed position to wide open position. The arm 69 is so arranged relatively to the throttle lever that it contacts the roller 68 in a late stage of the opening of the throttle and opens the valve 62 with the full opening of the throttle.

Fuel is delivered to the secondary carbureter from the nozzle 70. This nozzle is arranged in a screw plug 71 having the axial opening 72 communicating with the nozzle opening 70. A passage 73 is formed in the carbureter body and this is of two diameters, the smaller diameter receiving the screw plug 71 and the larger diameter of the passage being large enough to receive the head of the screw. The screw plug 74 is screwed into the lower end of the passage 73. The screw plug has the axial opening 75 from which the restricted radial opening 76 extends. A groove 77 is arranged around the screw plug forming an annular passage with which the radial opening 76 communicates. The passage 78 extends from the passage 74 and supplies fuel to the second nozzle. Preferably the passage 78 is extended through the body and the opening is closed by the screw 79.

In the operation of this secondary carbureter, the opening 61 controls the resistance to the air and forms with the nozzle what is known as a fixed orifice carbureter, the fuel being controlled by the restricted openings formed by the nozzle 70 and the opening 76 and the air being controlled by

the opening 61. The relations of these passages are such as to give to this secondary carbureter a richer mixture than the primary carbureter. The reason for this is that to get maximum power a richer mixture is desirable than that used under ordinary conditions. The primary carbureter here shown on account of the pick-up device hereinafter described is adjusted to a very lean mixture, 10 leaner than would be practical without such device and leaner than would be desirable except for this secondary carbureter. The mixture from the secondary carbureter is, therefore, not only richer than that of the primary carbureter but also richer than would be desirable even for maximum power, it being enough richer than would thus be desirable to supplement the lean mixture of the primary carbureter so that 20 the mixture as a whole is richer than commonly used under ordinary conditions. This gives to the carbureter a very sensitive control, an air velocity assuring atomization and a mixture giving the greater efficiency 25 in the ordinary range of operations, and at the same time great capacity and a rich mixture where high power is desired.

The valve 62 when closed cuts off the influence of the reduced pressure of the mixing 30 chamber on the nozzle 70. This nozzle under these conditions is subjected to atmospheric pressure.

When the throttle is suddenly opened in the carbureter the mixture is momentarily 35 leaner than it should be and this prevents a rapid pick-up. To obviate this difficulty, I have provided a device for delivering to the carbureter a supply of fuel momentarily supplementing that from the regular fuel 40 nozzle so as to give a rapid pick-up. At the same time the flow from the regular fuel nozzle is not interfered with. The tubular chamber 15 above the plug 16 forms an auxiliary fuel chamber. It is connected by 45 an inclined passage 80 which extends from the auxiliary fuel chamber 15 to the "Venturi tube" 47 so that any fuel delivered through the passage 80 is taken up by the rapidly moving air in the "Venturi tube." 50 A passage 81 extends downwardly from the bottom of the mixing chamber to the tube 80. A plunger 82 is arranged in the chamber 15. It forms a loose fit. This is particularly true with the lower end so that 55 when the plunger drops the fuel in the space below the plunger is forced up between the plunger and the walls of the chamber 15. A cylinder 85 extends upwardly from the chamber 15 and the extension 86 projects 60 from the plunger 82. A piston 87 is arranged on the upper end of the extension 86 and makes a sliding fit with the cylinder. The upper end of the cylinder 85 is connected by a passage 88 with the carbureter 65 at the discharge side of the throttle so that

the upper end of the cylinder is subjected to variations of pressure which take place above the throttle. The upper end of the chamber 15 is connected by a passage 89 with the mixing chamber below the throttle 70 and a second passage 90 extends from the mixing chamber to the chamber 15. From this it will be seen that the pressures below the piston 87 are the pressures of the mixing chamber and the pressure above the piston 75 87 is the pressure above the throttle.

The operation of the pick-up device is as follows:—With a small opening of the throttle, the pressure above the throttle is reduced sufficiently to effect the lifting of the plunger 82 through the differences in pressure below and above the piston 87. If, however, the throttle is suddenly opened, the atmosphere above the throttle more nearly approximates that in the mixing chamber below and the 85 difference in pressure on the piston under these conditions will not be sufficient to retain the plunger in its upper position and the plunger will, therefore, drop by gravity forcing the fuel upwardly along the lower 90 end of the plunger into and through the passage 80 delivering momentarily a given supply of fuel for enriching the mixture and insuring an immediate pick-up. When, however, the throttle is again moved to a more 95 nearly closed position, the difference in pressure above and below the throttle is increased, the pressure above the throttle being reduced and that below the throttle being increased and this difference in pressure acting on the 100 piston 87 is sufficient to again lift the plunger 82. When the plunger is in its upper position any suction that is created at the end of the passage 80 simply creates circulation by way of the passage 81. In the normal operation of the carbureter gasoline is deposited on the walls of the chamber 1. It is collected at the bottom, passes through the passages 81 and 80 and the passages 47 and into the air stream passing through the 110 "Venturi tube" so that there is a constant circulation. The auxiliary chamber is supplied from the gasoline so collected by way of the passages 81 and 80.

In this pick-up device there is no outside 115 connection either with the air or the fuel device and consequently the normal flow of air is not interfered with in any way but operates according to its normal capacity regardless of whether the pick-up is operating or not and the fuel being delivered through the nozzle is not in any way interfered with by the action of the pick-up so that there is no disturbance in these factors. The absence of any supplemental openings 120 to the atmosphere is also desirable in that if any special devices are used through which air is delivered to the carbureter the air for the carbureter will pass through these devices.

In the ordinary adjustment of a carbureter the adjustment is a compromise, a little richer than is required for best efficiency but better than the extremely lean mixture for pick-up. On the other hand, this over-rich mixture does not supply the requirements when the throttle is suddenly opened. With this carbureter a mixture leaner than would ordinarily be practical can be used for ordinary running and the pick-up device supplies all that is required for sudden openings of the throttle and the secondary carbureter supplies the quality for extreme power.

15 What I claim as new is:—

1. In a carbureter, the combination of a mixing chamber; means for delivering a normal supply of air and fuel to said chamber comprising a restricted passage; a 20 throttle valve; and devices sensitive and exposed alone to pressures within the carbureter at points as near the discharge as the restricted passage for momentarily supplementing the delivery of fuel when the throttle opens.

2. In a carbureter, the combination of a mixing chamber; means for delivering a normal supply of air and fuel to said chamber; a throttle valve; and devices sensitive 30 and exposed alone to pressures within the carbureter at the two sides of the throttle for momentarily supplementing the delivery of fuel when the throttle opens.

3. In a carbureter, the combination of a mixing chamber; means for delivering a normal supply of air and fuel to said chamber; a throttle valve; and devices sensitive 35 and exposed alone to pressures within the carbureter for momentarily supplementing the delivery of fuel when the throttle is open, said means for delivering fuel being independent of said devices.

4. In a carbureter, the combination of a mixing chamber; a throttle valve; a fuel 45 chamber; means for delivering air to the mixing chamber; a connection for delivering fuel from the fuel chamber to the mixing chamber; an auxiliary chamber receiving fuel from the mixing chamber; and devices 50 for automatically discharging fuel from the auxiliary chamber to the air to momentarily supplement the fuel from said connection when the throttle is opened.

5. In a carbureter, the combination of a mixing chamber; a fuel chamber; a throttle 55 at the discharge side of the mixing chamber; means for delivering air to the mixing chamber; connections for delivering fuel from the fuel chamber to the mixing chamber; an auxiliary chamber receiving fuel from the mixing chamber; and devices sensitive 60 to variations of pressure at the discharge side of the throttle for discharging the fuel from the auxiliary chamber to the air

to momentarily supplement the fuel from 65 said connections.

6. In a carbureter, the combination of a mixing chamber; a fuel chamber; a throttle at the discharge side of the mixing chamber; means for delivering air to the mixing 70 chamber; connections for delivering fuel from the fuel chamber to the mixing chamber; an auxiliary chamber receiving fuel from the mixing chamber; and devices sensitive to differences of pressure at the discharge and mixer sides of the throttle for 75 discharging fuel through the auxiliary chamber to the air to momentarily supplement the fuel from said connections.

7. In a carbureter, the combination of a 80 mixing chamber; a fuel chamber; a throttle at the discharge side of the mixing chamber; means for delivering air to the mixing chamber; connections for delivering fuel from the fuel chamber to the mixing chamber; an auxiliary chamber receiving fuel from the 85 mixing chamber; and devices operative upon the opening of the throttle for discharging fuel from the auxiliary chamber to the air to supplement the fuel from said connections.

8. In a carbureter, the combination of a mixing chamber; a throttle valve; a fuel chamber; a connection between the fuel chamber and the mixing chamber; means for 95 delivering air to the mixing chamber; an auxiliary chamber; a fuel connection for the auxiliary chamber; connections leading to said auxiliary chamber from the discharge side of the throttle and from the mixing 100 chamber; and devices actuated by said differences of pressure for discharging fuel from said auxiliary chamber to momentarily enrich the normal supply.

9. In a carbureter, the combination of a mixing chamber; a throttle valve; a fuel chamber; a connection between the fuel chamber and the mixing chamber; means for delivering air to the mixing chamber; an auxiliary chamber; a fuel connection for 110 the auxiliary chamber leading from the mixing chamber; connections leading to said auxiliary chamber from the discharge side of the throttle and from the mixing chamber; and devices actuated by said differences 115 of pressure for discharging the fuel from said auxiliary chamber to momentarily enrich the normal supply.

10. In a carbureter, the combination of a mixing chamber; a fuel chamber; a connection between the fuel chamber and the mixing chamber; an air passage leading to the mixing chamber; a throttle valve; an auxiliary fuel chamber; a plunger in the auxiliary chamber adapted to deliver fuel therefrom to momentarily enrich the normal mixture; air connections leading to the auxiliary chamber from the discharge side of the

throttle and the mixer side of the throttle; and a motor subjected to the differences of pressure through said connections for actuating said plunger.

- 5 11. In a carbureter, the combination of a mixing chamber; a throttle valve; a fuel chamber; means for delivering air to the mixing chamber; a connection for delivering fuel from the fuel chamber to the mixing 20 chamber; an auxiliary chamber receiving fuel from the mixing chamber; a plunger in the auxiliary chamber; and devices actuated by differences of pressure at the discharge and mixer sides of the throttle for actuating the plunger to discharge fuel from the auxiliary chamber on the opening of the throttle. 25
- 10 12. In a carbureter, the combination of a

mixing chamber; a throttle valve; a fuel chamber; means for delivering air to the mixing chamber; a connection for delivering fuel from the fuel chamber to the mixing chamber; an auxiliary chamber receiving 20 fuel from the mixing chamber; a plunger in the auxiliary chamber; and devices actuated by differences of pressure at the discharge and mixer sides of the throttle for actuating the plunger to discharge fuel from the auxiliary chamber on the opening of the throttle.

In testimony whereof I have hereunto set my hand.

FRANK H. BALL.
